Primary Examiner—Marcus A. Jackson

(57) **CLAIM**

The ornamental design for a LED lighting assembly, as shown and described.

DESCRIPTION

FIG. 1 is a perspective view of the primary embodiment of the LED lighting assembly of the present invention.

FIG. 2 is a top view of the LED lighting assembly that is identical to the left side view of the apparatus.

FIG. 3 is a first side view of the LED lighting assembly.

FIG. 4 is a second side view of the LED lighting assembly taken from a side that is disposed at a 90 degree angle with respect to the first side view; and,

FIG. 5 is a bottom view of the LED lighting assembly in accordance with the present invention.
